Primary Examiner — Ricky Pham

(57) **CLAIM**

The ornamental design for a shredder, as shown and described.

DESCRIPTION

FIG. 1 is a perspective view of the shredder showing my new design;

FIG. 2 is a front elevational view thereof;

FIG. 3 is a rear elevational view thereof;

FIG. 4 is a left side devotional view thereof;

FIG. 5 is a right side elevational view thereof;

FIG. 6 is a top plan view thereof; and,

FIG. 7 is a bottom plan view thereof.

The broken lines are for the purposes of illustrating portions of the shredder and form no part of the claimed design.
